UNITED STATES PATENT OFFICE.

ERNEST GODFREY LAPLANTE, OF MARLBORO, MASSACHUSETTS.

ELECTRIC-LIGHTED LEVEL.

1,176,374.

Specification of Letters Patent. Patented Mar. 21, 1916.

Application filed October 6, 1915. Serial No. 54,464.

To all whom it may concern:

Be it known that I, ERNEST G. LAPLANTE, a citizen of the United States, residing at Marlboro, Massachusetts, have invented a 5 new and useful Electric-Lighted Level, of which the following is a specification.

Among the important objects of the invention are to illuminate both a horizontal and vertical level glass by one electric bulb; 10 to provide one or more convenient switches or push buttons for controlling the light; to provide a lock for controlling the lamp circuit, and to provide new and useful construction and arrangement of parts as will 15 hereinafter appear.

The accompanying drawing shows one exemplification of the invention, but it is to be understood that the invention is capable of embodiment in different forms.

20 Figure 1 is a perspective view; Fig. 2 is a side elevation with the cover removed; Fig. 3 is a transverse section showing the push buttons and connections; Fig. 4 is a detail of the lamp socket; Fig. 5 is a transverse 25 section of the same; Fig. 6 is a transverse section of the lock switch or circuit breaker; Fig. 7 is a side elevation of same.

Reference character 1 designates a box-like housing having a removable side plate 30 or cover 2, secured by screws 3. This housing has suitable top flanges 4 for securing the housing to the wooden body of a level.

Suitably located in the housing is an opening 5 defined by a curved wall 6. This opening extends through the housing from side to side and communicating with it also is an aperture 7 in the top of the housing. The curvature of the wall 6 provides for the arrangement of two level glasses 8 and 9 at 40 right angles to each other so that the bubbles are observable through opening 5 from either side or from the top of the level.

At one side of the opening 5, in the wall 6, is a small light aperture 10, at the rear of 45 which is placed an electric bulb 11, usually cushioned against the inner side of wall 6 by a suitably apertured piece of felt 12 or other suitable cushioning device. The bulb is held by a clip or socket consisting of spring 50 pieces 13 secured to an insulated base 14. The threaded part of the bulb, constituting one terminal, may be easily snapped into the socket or clip in an obvious way. At some distance from the wall 6 is partition 15. 55 The dry cell 16 of any suitable form for the purpose is removably placed in the hous-

ing between partition 15 and the bulb. There are standard cells for this purpose, among which is a cell having an insulating sleeve, an exposed base constituting one of the terminals of the cell, and at the opposite end a metallic piece 17 constituting the other terminal. The cell is held in place removably and electrically connected as follows: 60 A piece of insulating material 18 is placed against partition 15, and against this insulator is a helical spring 19 to which a conductor is connected. This helical spring makes electric contact with the base terminal of the cell, and at the same time urges the cell 65 against the base terminal of the lamp bulb so that electric connection is made with the lamp at 17. The spring pressure applied to the cell also assists in holding the lamp in position against cushion 12. The cell 70 is further supported laterally by transverse partitions 21 suitably recessed to accommodate the cell, and when cover 2 is in position, the cell is firmly held in its position 75 until it is necessary to replace it. 80

Suitable controlling switches, usually in the form of push buttons 22, are placed in the sides of the housing and by suitable wiring 23, the appropriate terminals of the push buttons are connected with base 85 terminal of the cell through wire 20 and with a locked circuit breaking device through wire 24. Wiring of the adjacent push buttons 22 is sufficiently long to permit the cover 2 to be removed without disturbing the wiring. At the opposite end of the housing upon a suitably insulated base 25 is a circuit breaker or main switch 26 consisting of two contact pieces 27 and 28, usually made of spring metal. Back of contact 28 is insulating material 29, against which the end of the bolt 30 engages. The bolt is controlled by the key operated lock 31 of which the key hole is seen at 32 in Fig. 1. When the key is suitably moved the bolt is extended to bring contacts 27 and 28 together, and the bulb may then be lighted by pressing either of the push buttons 22, and when so lighted the opening 5 and both of the level glasses are clearly illuminated, but with very little consumption of current, owing to the fact that a very small bulb may be employed. When, however, it is desired to prevent the use of the lamp, the key is turned to retract bolt 30, and the 90 battery circuit is then broken between contacts 27 and 28, and manipulation of the 95

100

105

110

push buttons will be ineffectual to light the lamp.

Claim:

In a level, the combination of a housing 5 having a transverse opening with a curved wall, two level glasses arranged in said opening at right angles to each other, said wall having a lamp aperture, an electric bulb at said aperture to illuminate the

glasses, a contact clip to hold the bulb, a 10 battery cell, spring means to urge one terminal of the cell into engagement with the base terminal of the bulb, said means also serving to make contact with the other terminal of the cell, and a push button in circuit between said spring and said clip. 15
